US00D747338S

(12) **United States Design Patent**
Lee et al.

(10) **Patent No.:** US D747,338 S
(45) **Date of Patent:** ** Jan. 12, 2016

(54) **TELEVISION RECEIVER WITH GRAPHICAL USER INTERFACE**

(71) Applicant: **LG ELECTRONICS INC.**, Seoul (KR)

(72) Inventors: **Kunsik Lee**, Seoul (KR); **Uniyoung Kim**, Seoul (KR); **Gooryong Kang**, Goyang-si (KR); **Gangseub Lee**, Seoul (KR); **Hyejin Yu**, Yongin-si (KR); **Hyungnam Lee**, Anyang-si (KR)

(73) Assignee: **LG Electronics Inc.**, Seoul (KR)

(**) Term: **14 Years**

(21) Appl. No.: **29/455,854**

(22) Filed: **May 24, 2013**

(30) **Foreign Application Priority Data**

Nov. 28, 2012 (KR) 30-2012-0057072

(51) **LOC (10) Cl.** **14-04**

(52) **U.S. Cl.**

USPC **D14/487**

(58) **Field of Classification Search**

USPC D14/485-495

CPC G06F 3/04817; G06F 3/0482

See application file for complete search history.

(57) **CLAIM**

The ornamental design for a television receiver with graphical user interface, as shown and described.

DESCRIPTION

The FIGURE is a front view of a television receiver with graphical user interface showing our new design.

The dashed broken lines depict unclaimed portions of the article and form no part of the claimed design. The dash-dot broken lines define the bounds of the claimed design and form no part thereof.
